UNITED STATES PATENT OFFICE.

ALFRED DUCASBLE, OF PARIS, FRANCE, ASSIGNOR TO THE MANUFACTURED RUBBER COMPANY.

DESIGN FOR A FELLY.

SPECIFICATION forming part of Design No. 34,005, dated January 29, 1901.

Application filed January 15, 1900. Serial No. 1,564. Term of patent 14 years.

To all whom it may concern.

Be it known that I, ALFRED DUCASBLE, a citizen of the Republic of France, residing at Paris, France, have invented and produced a new and original Design for a Felly, of which the following is a specification, reference being had to the accompanying drawings, forming part hereof.

Figure 1 is a perspective and Fig. 2 a cross-sectional view of a felly having my design.

The leading feature of my design is illustrated in the drawings; and, generally speaking, it consists of a felly having a flat trough and sloping walls which curve outwardly, forming ogee curves free from sharp edges, the inner faces of said walls forming sharp corners at their unions with the base or trough.

In the drawings, *a* represents the walls, and upon their inner faces they slope outward, as shown, and these inner faces *b* are curved, more particularly as at *c*.

d represents the sharp corners formed by the inner faces and flat trough *e*.

Having thus described my invention, what I claim as new, and desire to secure by Letters Patent, is—

The design for a felly, substantially as shown and described.

In testimony whereof I have hereunto signed my name.

ALFRED DUCASBLE.

In presence of—

R. H. BRANDON,
J. L'HERMIT.
